UNITED STATES PATENT OFFICE.

GEORGE L. SMITH, OF PATTON, CALIFORNIA.

DESIGN FOR A GAME-BOARD.

SPECIFICATION forming part of Design No. 28,338, dated March 1, 1898.

Application filed December 31, 1897. Serial No. 665,244. Term of patent 7 years.

To all whom it may concern:

Be it known that I, GEORGE L. SMITH, residing at Patton, in the county of San Bernardino and State of California, have invented 5 a new and useful Design for a Game-Board, of which the following is a specification.

This invention relates to a new and useful design for game-boards; and it consists in the formation and arrangement of parts set forth 10 in the specification and illustrated by the accompanying drawings, in which—

Figure 1 is a perspective view. Fig. 2 is a top plan view. Fig. 3 is a longitudinal sectional view. Fig. 4 is a transverse sectional 15 view.

My design consists of a board A, having a

groove B formed about its edge, leaving a raised portion C, upon which are positioned at each end thereof the posts D. A longitudinal series of wickets E are arranged upon 20 the board in line with said posts, and the wickets F are positioned on opposite sides of said longitudinal series of wickets E.

Having thus fully described my design, what I claim, and desire to secure by Letters 25 Patent, is—

A design for a game-board, substantially as herein set forth.

GEO. L. SMITH.
